[57] **CLAIM**

The ornamental design of an insulated pouch for beer kegs, as shown and described.

DESCRIPTION

FIG. 1 is a top front perspective view of an insulated pouch for beer kegs showing our new design;

FIG. 2 is a side elevational view thereof, the opposite side elevational view being a mirror image;

FIG. 3 is a front elevational view thereof;

FIG. 4 is a rear elevational view thereof;

FIG. 5 is a top plan view thereof; and

FIG. 6 is a bottom plan view thereof.

FIG. 1

FIG. 2

FIG. 3

FIG. 4

FIG. 5

FIG. 6
